(57) **CLAIM**

The ornamental design for a lighting fixture, as shown and described.

DESCRIPTION

FIG. 1 is a bottom perspective view of a first embodiment the lighting fixture;

FIG. 2 is a top perspective view of the first embodiment of the lighting fixture;

FIG. 3 is a right side view of the first embodiment of the lighting fixture;

FIG. 4 is a front view of the first embodiment of the lighting fixture;

FIG. 5 is a left side view of the first embodiment of the lighting fixture;

FIG. 6 is a rear view of the first embodiment of the lighting fixture;

FIG. 7 is a top view of the first embodiment of the lighting fixture; and

FIG. 8 is a bottom view of the first embodiment of the lighting fixture.

FIG. 9 is a bottom perspective view of a second embodiment of the lighting fixture;

FIG. 10 is a top perspective view of the second embodiment of the lighting fixture;

FIG. 11 is a right side view of the second embodiment of the lighting fixture;

FIG. 12 is a front view of the second embodiment of the lighting fixture;

FIG. 13 is a left side view of the second embodiment of the lighting fixture;

FIG. 14 is a rear view of the second embodiment of the lighting fixture;

FIG. 15 is a bottom view of the second embodiment of the lighting fixture; and,

FIG. 16 is a top view of the second embodiment of the lighting fixture.

The broken lines shown on the drawings depict portions of the lighting fixture that form no part of the claimed design.

1 Claim, 10 Drawing Sheets
